UNITED STATES PATENT OFFICE.

CLARENCE A. VETTER, OF PITTSBURGH, PENNSYLVANIA.

LAMP-SOCKET.

1,209,909

Specification of Letters Patent. Patented Dec. 26, 1916.

Application filed December 26, 1913. Serial No. 808,663.

To all whom it may concern:

Be it known that I, CLARENCE A. VETTER, a citizen of the United States, residing at Pittsburgh, in the county of Allegheny and State of Pennsylvania, have invented certain new and useful Improvements in Lamp-Sockets, of which the following is a specification.

My invention refers to improvements in the class of sockets for incandescent lamps.

It has for its object to provide a socket adapted to operate for making and breaking the current by partial rotation of an actuating stem within the base, by means adapted to impart an intermittently partial rotating action to the stem, the device being provided with co-acting spring actuated elements whereby the completion of the operation is effected to insure a quick make-and-break contact of current-establishing mechanism, similar to that shown and described in my companion application filed herewith, bearing the Serial Number 808664. In said application, the operating stem is free to move continuously and intermittently in either direction. In the present invention, the stem is actuated intermittently always in the same direction, by means of co-acting ratchet mechanism and means, as a pull chain, or push bar, for primarily imparting movement to the ratchet mechanism.

The invention as constructed, and for the purpose of accomplishing the objects in view, consists generally of a base portion of insulating material having the usual terminal connections and the central and screw shell contact portions for engagement with the lamp base; an intermittently operative actuating stem; a make-and-break circuit opening and closing device thereon having a lost motion connection with the stem; a fixedly attached spring-actuated throw device on the stem; interengaging ratchet mechanism; and means for primarily actuating the ratchet mechanism, as shall be more fully hereinafter described.

Referring now to the drawings illustrating preferred forms of the invention,— Figure 1 is a vertical sectional view through the socket, indicated by the section I. I. of

Fig. 3, in the direction of the arrows α , α . Fig. 2 is a similar vertical sectional view at right angles of Fig. 1, indicated by the section line II. II. of Fig. 3. Fig. 3 is a plan view of the socket, corresponding to Fig. 1, 55 the outer shell being removed. Fig. 4 is a partial sectional view, similar to Fig. 1, taken on the line I. I. in the direction of the arrows y , y . Fig. 5 is a similar sectional view, showing the completion of the operation. 60 Fig. 6 is a partial sectional view, taken on the line VI. VI. of Fig. 3 in the direction of the arrows. Fig. 7 is a similar sectional view, taken on the line VII. VII. of Fig. 3. Figs. 8 and 9 are enlarged detail views 65 showing the operative mechanism of the construction above illustrated. Fig. 10 is a collective illustration in detail, showing the several co-acting working parts of the actuating mechanism in perspective, and in their 70 related co-acting arrangement. Fig. 11 is a vertical sectional view, similar to Fig. 1, showing a modified construction utilizing a push button. Fig. 12 is a partial similar view, showing the push button thrust inwardly to effect the shifting operation. Figs. 13 and 14 are enlarged detail views, 75 similar to Figs. 8 and 9, showing the mechanism utilizing the push bar operation. Fig. 15 is a sectional plan view on the line XV 80 XV. of Fig. 11.

In the drawings, the insulating base of the socket is composed of two parts, a and b , of porcelain or other suitable insulating material, fixedly connected in any suitable 85 manner, as by screws c and d , said screws extending inwardly from the opposite sides of the insulating members a and b and being tapped into connecting bridge pieces g . Said bridge pieces provide for the mounting 90 of binding screws 4 , by which the usual main supply wire terminals e are connected with the base.

The lower base member b is provided with the usual screw shell 2 for receiving the base d of the lamp D of the usual construction, and having the central contacting terminal portion d' . Shell 2 is fixedly connected with the base member b by the screws 3 , 3 , one of said screws, as stated, being in electrical 100

connection with the mounting for the terminal binding screw 4, as shown in Figs. 1 and 4. One of the supply wires *e* is connected by its terminal with the said binding screw 4, the other contact wire terminal *f* being connected by the other binding screw 5 and bridge piece *g'*, with an upper spring contact terminal 6, fixedly mounted within the upper portion of the socket and to member *a* thereof by screw 7. As shown, the inner central portion of members *a* and *b* is hollowed out for clearance of these parts and of the other operating elements, as will be clearly understood.

15 The actuating element of the socket is the intermittently rotatable stem 8 mounted in suitable transverse bearing bars 9, 9, inserted between the meeting portions of the base members *a* and *b*, and in receiving 20 sockets therein, whereby the bearings 9 are fixedly held in position. Stem 8 is provided with an actuating ratchet wheel 10, fixedly secured to the stem by soldering or other suitable means, having inwardly extending 25 ratchet teeth 11, preferably arranged equidistantly around the inner face of the wheel and at quartering positions thereon.

Freely mounted upon stem 8 is a co-acting 30 actuating, intermittently operative pawl wheel 12 having one or more, preferably two, ratchet teeth 13. Wheels 10 and 12 are conveniently made of sheet metal, the ratchet teeth being punched or sheared and pressed outwardly from the disk forming 35 the wheel, as clearly shown in Fig. 10.

In the construction shown in the principal figures of the drawings, I utilize a 40 pull chain 14, of suitable construction, having a suitable terminal 15, which chain passes around a circular supporting shell 16, having a slotted terminal 17, with which the end of the chain is removably connected. The shell 16, which constitutes a partly cylindrical bearing for the chain, and is provided with a guarding flange 18 at one side 45 thereof, is fixedly connected with the pawl wheel 12 in any suitable manner, but preferably through an insulating disk 19 of fiber or other suitable material. Such insulating disk is of the form shown in Figs. 50 9 and 10, and is provided with a shoulder 20 adapted to abut against a limiting shoulder 21 of the porcelain base *b*, at the termination of the intermittent rotation, upon 55 pulling down the chain.

The chain support or shell 16, and also the pawl wheel 12, are conveniently connected with the intervening fiber disk 19 by means of anchoring tangs 22, 22, respectively, which pass through receiving apertures 23 of the disk, and are clenched or bent over on the opposite side, as clearly shown in Fig. 8.

For the purpose of retracting the mechanism at the termination of the chain pull 65 operation, I employ a retracting spring 24, coiled around stem 8, fixedly connected at one end by its terminal 25 to a holding plate or bar 26, its other or free end being hooked around a projecting lug or hook 27, of pawl wheel 12. The insulating disk 19 is cut out or slotted, as indicated at 28, for providing clearance of the spring and hook, the spring thus making direct connection through the insulating disk with the pawl wheel. In 70 addition to its retracting function at the completion of the operation, the spring provides for maintaining constant pressure of pawl wheel 12 against ratchet wheel 10, for effecting interlocking engagement of the tooth or teeth 13 with teeth 11, to intermittently partially rotate stem 8, while at the same time allowing the pawl wheel 12 to recede against the spring pressure longitudinally, along stem 8, sufficient to ride over the 75 next adjacent ratchet tooth 11, to make a new hold or engagement with said tooth, the spring operating to again press the disk 12 forwardly to seat tooth 13 behind tooth 11. On the back movement, the reverse rotation of the disk 12 is arrested by the flat face 29 of the insulating disk 19, again seating upon the inner bottom of the lower insulating base *b*.

When it is desired to utilize the push bar 95 construction illustrated in Figs. 11 to 14 inclusive, the chain pull mechanism is substituted by a push bar 30 having a series of rack teeth 31 co-acting with a segmental rack 32 fixedly secured to an annular supporting segmental frame 33. Said frame thus takes the place of the chain support 16, being secured to the insulating disk 19, the several parts being constructed and adapted to operate as above described, with 100 the exception that movement is imparted upon inward thrust of stem 30 against retracting action of spring 24, the spring effecting reverse movement, and thrusting the stem 30 outwardly for the next operation. 105 The stem is provided with a button terminal 30', preferably of insulating material mounted within a receiving opening 34 in the lower base, as clearly shown.

The operation of the preliminary actuating mechanism above described, either by the pull chain or the push rod, effects partial rotation of stem 8 to a sufficient extent to bring into action the accelerating spring-actuated mechanism for completion of the 110 throw to effect quick make or break of the contact mechanism, supplemental to such preliminary actuation. For the purpose of effecting such supplemental accelerated movement of stem 8, and its conductor block, 115 I provide a rectangular block 35 fixedly se-

cured or mounted on the stem by soldering or other suitable means, having opposite parallel faces which are normally embraced between the inwardly pressing spring leaves 36, 36, of a resilient clevis, the base 37 of which is fixedly secured to the lower insulating base member *c* by a holding screw 38 or other convenient means.

The conductor block 39, of suitable conducting material, as brass, is loosely mounted upon stem 8, which passes through a central loose mounting opening therein. The block is provided with a central recess for clearance of a transverse actuating pin 40, adapted to provide for initial movement of pin 40 upon actuation of stem 8, such central clearance being bounded within the opposite transverse shoulders 41, 41; against which the ends of pin 40 bear, at or about the time when the stem 8 has been turned for, say, one eighth of a revolution, so as to move the controlling block 34 around to the position indicated in dotted lines in Fig. 7. Such action spreads the spring leaves 36, 36, apart, as also indicated in dotted lines, by the separating action of the corners of the controlling block 35. The action of springs 36, 36, is such that they will effect the completion of the rotation of stem 8 upon slightly further movement and at greatly accelerated speed by closing inwardly against the next adjacent parallel sides of the controlling block. This operation thus effects the completion of a one-quarter rotation of the stem, and is performed entirely independent of the chain pull or push bar mechanism, due to the free movement of the stem in the direction of its rotation, and action of springs 36 on block 35. As shown, block 39 is hexagonal in shape, thus providing two faces sloping toward the ends at each side from the widest middle portion. By this construction the movement of the block and its action with relation to the contact springs 6 and 42 is eased and facilitated, in connection with the controlling block 26 and its own lost motion connection with stem 8.

The conductor block 39 is mounted, as described, upon stem 8 for partial lost motion movement thereon by stem or pin 40, and is itself carried around with the stem, by action of the controlling block, as described, effecting its corresponding accelerated movement to make or break the circuit between the co-acting conductor spring members. One of such spring members 6 has been described. The other contact spring member 42, of considerable resiliency, is connected by nut 43 and screw stud 44 through the lower central portion of base member *b* with the central contact 45 against which engages the central contact portions *d'* of the lamp socket *d*.

The range of resilient movement of spring 62 is sufficient to engage against the end of conducting block 39, as in Fig. 6, to transmit the current, and also to engage the side of block 39, when turned a quarter way around to open position, whereby to hold it inoperatively for maintaining an open circuit, as indicated in dotted lines in the same figure. The construction thus provides for positively holding the conductor block in either open or closed arrangement. 75

The construction and operation will be readily understood from the foregoing description. The opposing portions of conductor block 39 being of a sufficient distance apart will tightly engage the springs 6 and 42 when in circuit-establishing position, as in Fig. 6, and will be quickly thrust into such position by action of the controlling block 35 and springs 36, 36. Likewise, in opening the circuit upon partial rotation of the same, the completion of the movement is effected by the controlling block, quickly throwing the conductor block around out of contact, and to the intermediate open position. The operation as thus described is intermittently continuous, effecting a quick make or break of the circuit upon a preliminary actuation by the operating mechanism, the last portion of the operation being effected automatically in the manner described. 95

What I claim is:

1. A lamp socket consisting of a two-part insulating base having external contacts for a lamp and internal circuit terminals, an actuating stem, a hexagonal conductor block loosely mounted on the stem and adapted to engage said terminals, a ratchet wheel fixed on the stem, a pawl piece loosely mounted on the stem and adapted to be engaged by the ratchet wheel and operatively connected to the conductor block, a spring coiled about the stem having one end fixed to a rigid member and the other end attached to and pressing against the pawl piece, whereby to force the ratchet wheel and pawl piece into engagement and to return the pawl piece to normal position after each operation, and means externally operative to turn the pawl piece. 110 115

2. A lamp socket consisting of a two-part insulating base having external lamp contacts and internal spring contacts, a hexagonal conductor block adapted to engage said spring contacts having a central opening and transverse shoulders, an actuating stem extending through the conductor block, a pin through the stem adapted to engage the shoulders of the conductor block on partial rotation of the stem, a ratchet wheel fixed on the stem, a pawl piece loosely mounted on the stem and adapted to engage the ratchet wheel, a spring coiled about the 120 125

1
stem having one end fixed to a rigid member and the other end attached to and pressing against the pawl piece, whereby to hold the pawl piece and ratchet wheel in engagement and to return the pawl piece to normal position after each operation, and means externally operative to actuate the pawl piece, whereby the conductor block is suc-

cessively thrown into and out of engagement with the spring terminals.

In testimony whereof I hereunto affix my signature in the presence of two witnesses.

CLARENCE A. VETTER.
